UNITED STATES PATENT OFFICE.

FREDERICK W. PARSONS, OF CLEVELAND, OHIO.

TURRET-LATHE.

1,387,305.

Specification of Letters Patent.

Patented Aug. 9, 1921.

Application filed January 7, 1920. Serial No. 349,926.

To all whom it may concern:

Be it known that I, FREDERICK W. PARSONS, a citizen of the United States, residing at Cleveland, in the county of Cuyahoga and State of Ohio, have invented certain new and useful Improvements in Turret-Lathes, of which the following is a specification.

This invention is an improvement in the style of turret lathe comprised in my application for Letters Patent of the United States, Ser. No. 310,671, and particularly in means for clamping the turret firmly on its base to prevent possible looseness and chattering while at work, all substantially as shown and described and particularly pointed out in the claims.

In the accompanying drawings, Figure 1 is a plan view of the turret and the slidable support therefor. Fig. 2 is a vertical sectional elevation centrally lengthwise through Fig. 1, omitting the operating lever. Fig. 3 is a plan view on a line horizontally through the machine on line 3—3, Fig. 2, showing one position of the parts illustrated therein, and Fig. 4 is a similar view to Fig. 3 but with the said parts in the reverse position, as hereinafter fully described.

Fig. 5 is a longitudinal vertical section of the turret saddle so called, and of the slide or immediate support therefor and a portion of the turret. Fig. 6 is a plan view of the chain of gears and parts adapted to rotate the turret in one direction. Fig. 7 is a cross section through the turret and its immediate supports.

Having reference, first, to the features or parts shown herein corresponding to those found in the above cited application, we have the turret 7, the so-called slide or slidably support 8 on which the turret is rotatably mounted and the saddle 9 adjustably seated on the fixed bottom or base 2.

The turret and its immediate support or slide are adapted to be moved back and forth within limits by the hand lever 10, which is linked at its outer end to a bracket 11 fixed on said saddle and pivotally engaged at 6 on said slide. When the slide and turret are retired a heavy coiled spring 16 is compressed to store up power to rotate the turret to predetermined position for work and at the same time the tapered locking bolt 15 is withdrawn from a tapered hole in the bottom of the turret which corresponds to the work position of a tool in the turret, and the

check pawl 17, Fig. 5, is released, thus permitting the said spring to act and rotate the turret through the medium of the intervening ratchet member 18 and the three several gears 19, 20 and 21. The ratchet mechanism set to turn the gears and turrets releases the spring 16 the instant that the hook 37 is released from shoulder 36. This release occurs through the pivoted lever 39, which has an inclined end projection 40 adapted to slip under the beveled end of pawl 17, and the other end of lever 39 carries the turret locking bolt 15. The said end 40, however, as a first movement for release of bolt 15 to free the turret, rides up on the incline 41 and before it reaches hook member 37 to set it free from catch 36.

The travel or movement of the slide 8 is relatively short in compressing the spring and releasing the hook 37 of the pawl 17 to permit the spring to act, and only partial rotation of ratchet member 18 is given by link 32 under the impulse of the spring when pawl 17 is released.

In operation with the foregoing parts each movement of the slide 8 by lever 10 away from the work will first cause the locking bolt 15 to be withdrawn from the turret; then hook 37 on pawl 17 engages the shoulder 36 and spring 16 is compressed and the ratchet member 18, Fig. 2, rotated to an effective operating position. Trip lever 39 then releases hook 37 and the spring 16 expands and rotates the series of gears described and the turret, and stop screw cylinder 53 also is rotated, as hereinafter described. On reversal of lever 10 the slide 8 is carried forward as far as the stop screws 51 will permit and in the initial stages of this movement the turret locking bolt 15 is raised into one of the series of holes in the bottom of the turret, thus locking the turret against rotation and alining a corresponding working tool. The stop screws 51 referred to correspond in number to the tools in the turret, and all are mounted in and extend through the cylinder 53 carried by the slide 8 and driven by the shaft 28 and the spiral gears 25 and 27, all as set forth in the preceding application above referred to.

Now, having the lathe constructed and adapted to operate as thus generally outlined, the invention which this application is designed to cover has to do more especially with the means for clamping the turret

tightly upon its seat on the slide 8 so as to avoid any possible looseness and consequent chattering, as is liable to occur in case the turret is not thus firmly clamped in place 5 when in use. It will be noticed that the turret is shown as having an annular downwardly extending flange 42 at its bottom which seats quite snugly upon or in a corresponding annular recess in the somewhat 10 raised seat 43 of the slide member 8. This construction in itself tends to center the turret on its seat and the locking bolt 15 serves as a definite stop against rotation, but neither construction serves the further need 15 of anti-chattering mechanism. Such mechanism in this instance comprises means for automatically clamping the turret firmly upon its seat and for releasing the same to permit rotation, and in this instance consists of a clamping bolt 24 extending down 20 through a sleeve or bushing *b* in the axial center of the turret and through the slide 8 and beneath the same to make clamping and other engagements. The head of the bolt 25 rests upon the flanged top of the said sleeve in a recess in the turret and a clamping plate *P* is fixed upon the bottom of the slide 8 by screws *s* and spaced apart therefrom by spools or the equivalent, to afford room between 30 said plate and the slide for the actuating gears 20 and 21. The gear 20 is supported on a screw-threaded shaft 29 and gear or pinion 21 is mounted and splined on a reduced portion of the sleeve *b*, as is also 35 the spiral gear 25 next above 21, and which is meshed by gear 27 on shaft 28. The clamping plate *P* is of such firmness as to resist all pressure when the nut *n* is tightened on bolt 24 to clamp the turret on its seat, and 40 sleeve *b* extends only to said plate while bolt 24 projects through the clamping plate *P* and has its screw-threaded end engaged by the nut *n* bearing against said plate. The said nut has a short arm or lever *a* by which 45 the nut is adapted to be rotated to clamping and releasing positions alternately and automatically as the turret carrying slide is moved back and forth. In these operations and assuming that the turret is moving away 50 from the work, the clamping screw is loosened preliminary to rotation of the turret, and unclamping is effected when the roller *r* or equivalent projection on the bottom side of the nut arm *a* rides into engagement with the inclined wall of a cam *c* which is adjustably seated in base 9 but directly in the line 55 of travel of said arm and its roller. The cam comprises a round head divided centrally by a cam groove, or in other words 60 the cam comprises two upright lugs 4 with straight inner edges spaced apart and extending beyond each other at opposite ends respectively, so that when the cam engaging surfaces are set in inclined relation to the line of travel of the nut the arm *a* will auto-

matically strike the projecting end of one lug 4 and turn inward between the lugs to position until it is free to pass out of the opposite end of the cam groove, see Figs. 3 and 4. As this occurs the nut *n* is rotated 70 sufficiently to release the clamping pressure of bolt 24 upon the turret, so that it may be freely rotated during a continuing movement of the slide and through the agencies provided. When the turret is stopped and the 75 slide reversed to advance the new tool to working position the lever *a* is given a reverse turning movement by cam *c* as roller *r* passes into the rear end of the cam groove and out of the front end on its way forward 80 with the slide and turret, thereby effecting clamping of the turret upon its seat by a tightening movement of nut *n*. Only a slight movement is required for effecting clamping results, and the cam surfaces may 85 be set at approximately 45 degrees to the line of movement of turret and slide, or more or less inclination can be given by rotating the cam member in its seat by means of a pair of screws *d* and push pins or bolts *g* which 90 extend through the side of base 9 into bearing engagement with two depending pins *h* on the bottom side of the cam member, see Figs. 2 and 3. That is to say the nut *n* may be tightened more or less by rotary adjustment of cam *c* which controls the degree of turning movement of arm *a* and the nut, and such adjustment and fixing of the cam member in a predetermined position can be accomplished by turning the screws *d* from 100 the outside of the saddle. One screw *d* acts as an adjusting screw and the other screw *d* serves as a set screw, and their functions are alternative dependent upon the direction of turning movement given to the rotatable cam 105 member.

In summary, when the turret is retired the clamping screw is automatically released and also is automatically tightened again upon forward movement of the turret. This 110 clamping effect supplements the locking action of bolt 15 which engages the bottom of the turret and prevents rotation, and both are automatically obtained by the movements of the slide on the saddle. Any suitable pitch of thread on the bolt may be used to effect a longitudinal movement of the bolt when the nut is turned, or I may utilize other means for obtaining this movement and a clamping of the turret automatically during the travel of the slide. Broadly considered, the invention comprises co-acting mechanisms adapted to clamp and unclamp the turret automatically during the 115 interval of movement of the slide back and forth in respect to the work.

What I claim is:

1. In a lathe, a rotatable turret and a support therefor and clamping means extending through said parts adapted to bind the 130

turret on its support, rotatably adjustable device stationed opposite said support adapted to operate said clamping means, and means accessibly located outside of the 5 lathe adapted to fix said device in different working positions to operate said clamping means in variable degree.

2. In a lathe, a rotatable turret and a fixed base and a support for the turret 10 slideable on said base, a bolt and a tightening nut thereon adapted to clamp the turret on said support and said nut having a lateral arm with a roller at its end, a rotatable cam member fixed on said base having opposite 15 inclined surfaces with a space between adapted to receive said roller and rotate said nut alternately in opposite directions, adjusting screws to rotate and fix said cam member in different position, and means to 20 move said turret support back and forth and thus bring said roller into engagement with said inclined surfaces and release and lock said bolt.

3. In a lathe, a turret adapted to rotate 25 intermittently, a bolt adapted to clamp the turret against rotation, a device located beneath said turret adapted to lock and unlock said bolt, a rotatable cam member adapted to actuate said device, and screw 30 and bolt means adapted to adjust and fix said cam member with its cam surfaces in

different working positions relative to said device.

4. In a lathe, a turret, and means adapted 35 to automatically clamp the turret in an immovable position, comprising a rotatable cam and a pair of adjusting set screws adapted to fix said cam in different positions.

5. In a lathe, a slide and a saddle therefor, a turret mounted upon said slide, a clamping device for said turret at the bottom of said slide, a movable cam member mounted upon said saddle adapted to be engaged by said device, and means operable 45 from the outside of the saddle adapted to adjust and fix said member in different working positions.

6. In a lathe, a slide, a turret mounted to rotate upon said slide, gears within said slide adapted to rotate said turret, a clamping plate beneath said gears, a clamping bolt extending through said turret and gears and said plate, a tightening device for said bolt bearing against the bottom side of said plate, and stationary means adapted to be 50 engaged by said device in the movements of the slide.

Signed at Cleveland, in the county of Cuyahoga, and State of Ohio, this 28th day of October, 1919.

FREDERICK W. PARSONS.
